FOREIGN PATENT DOCUMENTS

157827 1/1905 Germany .

FIG. 1 is a perspective view of a bow stopper showing my new design;

FIG. 2 is a perspective view in an alternate position thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of a stringed instrument bow is for illustrative purposes only and forms no part of the claimed design.
